JOHN A. BASSETT, OF SALEM, MASSACHUSETTS.

Letters Patent No. 66,067, dated June 25, 1867.

IMPROVED APPARATUS FOR CARBURETTING AND REGULATING THE FLOW OF GAS.

The Schedule referred to in these Letters Patent and making part of the same.

TO ALL WHOM IT MAY CONCERN:

Be it known that I, JOHN A. BASSETT, of Salem, in the county of Essex, and State of Massachusetts, have invented a new and useful Improvement in Gas-Carburetters and Regulators; and I do hereby declare that the following is a full, clear, and exact description of the same, reference being had to the drawing annexed to this specification.

The object of this invention is to arrange a gas-carburetting chamber with large evaporating surfaces in a comparatively small space, by means of which the gases are retained longer in contact with the fluid to be vaporized, and by which it becomes more thoroughly charged with the vapor of the hydrocarbon; and to combine with the carburettor a gas-governor of peculiar construction and arrangement, so that the flow of the gas to the burners may be regular, and at the most economical burning pressure, independent of the pressure in the street mains from the station gas-holder. In charging gases with the vapors of a hydrocarbon it is desirable to keep the gas as long as possible in contact with the liquid and its vapor, and to cause it to pass slowly over a large surface charged with the vapor: the degree of saturation depending upon the length of time which the gas is kept in contact, and allowed to absorb and become charged with the vapor. In this invention a large surface, both evaporating and capillary, is provided, and in combination with channels formed so that the gas passes circuitously over and through the vapor, repeating the operation through successive chambers until the gas is fully saturated. This is accomplished in a very compact form of apparatus, not difficult to construct, and its operation is certain and effective. The regulator is of the class known as diaphragm regulators, using a diaphragm of flexible material instead of a small gas-holder and mercury seal, and is made of thin sheet metal; the diaphragm being made of leather in combination with a sheet of thin malleable metal; the object being to produce a regulator easily and cheaply made, the diaphragm being saturated with a preservative compound, which, in combination with the sheet metal, makes it perfectly gas-tight. The use of diaphragm regulators has been much restricted in consequence of the material of which the diaphragm is composed being readily acted upon by the gas, and by the corrosive action of the sulphurous acid in the gas, soon becomes useless, and from the method commonly in use for uniting the two parts of the shell it has been difficult to make a perfectly gas-tight joint at the circumference. The shell of this regulator is composed of thin sheet metal, which is so formed at the circumference where the diaphragm is secured that a perfectly gas-tight joint is made, the whole arrangement being very durable, inexpensive, and easily put together. In the drawings—

Figure 1 represents an elevation of the carburettor and regulator.

Figure 2, a plan of one of the sections of the carburettor.

Figure 3, an enlarged detached sectional elevation of the regulator.

Figure 4, section of diaphragm.

Similar letters of reference indicate like parts in all the figures.

The carburettor A is an upright cylindrical chamber, made of any durable sheet metal. It is divided by horizontal disks B extending entirely across the chamber, about three inches apart, which in effect makes a series of shallow pans containing the hydrocarbon liquid. The gas inlet is shown at C. Upon each of these pans is placed an upright partition, D, in a spiral form, so that the gas is compelled to pass through the circuitous passage made by the partition wall, slowly over the entire surface of the disks B. Each of the pans has this spiral partition wall, and the gas passes from one to the other through the openings b b b, and through the regulator to the outlet M. The partition wall D is covered with cotton or other fibrous material, as an evaporating surface, and the space between the partition is filled with a capillary material. I prefer to use for this purpose the material indicated in my patent of January 1, 1867. The essential feature of the carburetting device here described is thus shown to be the slow passage of the gases through the circuitous channels formed by the partition walls, combining both an evaporating surface throwing off vapors, and a capillary material saturated with the liquid through which the gas is compelled to pass. This operation being performed in the successive chambers, the gas is fully charged with the hydrocarbon in a very small space. The shell of the regulator is made in two parts, E and F, and is formed by spinning, as it is termed, into the semispherical shape shown. The lower shell E has a flange, G, into which the upper shell fits. Between the shells at the circumference the diaphragm H is placed, and a part of the angle flange G of the shell E is closed firmly down upon

the flange of the shell F, riveting the diaphragm firmly in place and making a gas-tight joint. The upper shell F has an opening for the purpose of placing weights on the diaphragm for the purpose of controlling the pressure. This opening may be closed by the cover. The diaphragm H is made of thin leather, and I prefer to use tanned deer-skin for this purpose, as being more flexible, and possessing a greater degree of toughness than any I am acquainted with. I use two layers of leather, and between the layers I place a sheet of thin flexible malleable metal. Either copper, brass, or tin-foil may be used for this purpose. This diaphragm effectually prevents the exosmose and endosmose action of the gases, and entirely obviates the many objections to this class of regulators. The metal used for this purpose should be very thin, so as not to interfere with the raising and lowering of the diaphragm when acted upon by the pressure of the gas. The two layers of leather, after being saturated with the composition described, with the metallic sheet between, should be pressed in a screw-press so as to unite the parts firmly together. The gas passes from the carburettor through the valve opening K, and pressing against the diaphragm H raises or lowers the valve L according to the pressure of the gas, and, enlarging or diminishing the opening, regulates the pressure. The gas passes to the burners through the outlet pipe M. The diaphragm is thoroughly saturated with a composition made by melting paraffine, and adding to ten parts of melted paraffine three parts of carbolic acid and three parts of sperm oil.

Having thus fully described the nature of my invention, what I claim, and desire to patent, is—

1. A regulator, in combination with a closed carburettor, so as to regulate the flow of gas after being carburetted without risk of leakage, substantially as described.
2. The construction of a gas regulator, substantially as shown and described.
3. Retaining the diaphragm H in place, and the gas joint made at the flanges, substantially as specified.
4. A diaphragm prepared with the composition described, or its equivalents, when used for this purpose, substantially as set forth.
5. A diaphragm composed of two or more sheets of flexible material enclosing a sheet of malleable metal, in the manner and for the purpose as shown and described.

JOHN A. BASSETT.
